UNITED STATES PATENT OFFICE.

EARL H. OBERTOP, OF GOLDFIELD, NEVADA.

BRUSH.

1,183,757.

Specification of Letters Patent. Patented May 16, 1916.

Application filed March 15, 1915. Serial No. 14,315.

To all whom it may concern:

Be it known that I, EARL H. OBERTOP, a citizen of the United States, residing at Goldfield, in the county of Esmeralda, State 5 of Nevada, have invented new and useful Improvements in Brushes, of which the following is a specification.

This invention relates to brushes, and especially to tooth brushes in which a dentifrice container is a part of the brush.

It is an object of this invention to provide in a brush a dentifrice container, the brush being portable and so constructed that the dentifrice will not be spilled or wasted 15 as the brush is jostled about, but from which the dentifrice may be applied as desired.

It is another object of this invention to provide a tooth brush with a hollow handle for containing the dentifrice, and with 20 means whereby a tooth paste or liquid may be forced through the brush back into the space between the bristles, or whereby a powder may be dispensed from the brush handle.

I attain these objects by the brush illustrated in the accompanying drawing, in which:

Figure 1 is a perspective view of my improved toothbrush. Fig. 2 is a vertical section through a brush in which a paste or liquid container is secured. Fig. 3 is a vertical section with the handle removed and showing a collapsible tube secured to the brush. Fig. 4 is an elevation partially in 35 section showing the handle arranged for the dispensing of tooth powder. Fig. 5 is an enlarged section taken on line 5—5 of Fig. 2. Fig. 6 is a vertical cross section taken on the line 6—6 of Fig. 4.

Referring more particularly to the drawing, my improved brush comprises a hollow handle 7 to which is secured a brush back 12 with a valve 15, mounted therein controlling a port 10 which opens into the 45 bristles 11.

More specifically, the brush comprises a substantially rectangular brush back 12 of the usual form having a bore 13 extending longitudinally therethrough, and enlarged 50 at one end 14 forming a seat 9 for a valve 15. The enlarged portion 14 of the bore has one of its walls pierced by a port 10 which opens into the bristles 11. Mounted within the bore 14 for reciprocation therein is 55 a piston valve member 15 which is abutted at one end by a spring 16. Spring 16 is re-

tained within the bore 14 by a closure screw 17, and normally presses valve 15 against seat 9. By removing the screw 17, the spring 16 and valve 15 may be removed and the bore in the brush cleaned. Bristles 11 are preferably secured to the brush back by being mounted in a bristle back 18 which is secured to the brush back. The bristle back 60 may be of the rubber set type if desired, that is, the bristles are embedded in rubber or some composition.

Secured to the brush back 12 and preferably integral therewith is a shank 8 which is flared and has a hollow enlarged extension 21. Shank 8 is reduced in diameter and exteriorly threaded as at 19, a shoulder 20 being formed thereon for abutment of the hollow handle 7. The bore 21 of hollow shank 8 is interiorly threaded to receive a 75 threaded neck 22 of a collapsible tube member 23 which is adapted to seat within the hollow handle 7. The handle 7 comprises a cylindrical member which has a bore open at one end, the open end being interiorly 80 threaded for engagement with threads on member 19. The closed end 24 is reduced in diameter and exteriorly threaded to engage with threads on the closure cap 25. Closed end 24 also has perforations 26 which 85 are for the purpose of dispensing tooth powder, when powder is placed in the container. An imperforate disk 27 of the same diameter as the bore in the handle 7 is loosely mounted therein for closing either 90 end of the bore.

To load my improved brush with tooth paste or a liquid, the handle 7 is unscrewed from the shank 8. Cap 25 is then unscrewed from handle 7 and disk 27 is placed over the 95 perforated end 24 closing the end, and cap 25 is then replaced. The collapsible tube 23 loaded with tooth paste or liquid is screwed into place in the shank 8, and the handle 7 is then placed thereover and secured to the 100 shank. The brush is now loaded and may be carried around in the pocket or elsewhere without danger of losing any of the dentifrice. The only outlet of the container is through port 10 which is closed by valve 105 15 resting over the port and abutting against seat 9 closing bore 18, in which position it is held by spring 16.

To use the brush the hollow handle 7 is unscrewed from the shank, the sides of the 110 collapsible tube 23 compressed, forcing a charge of dentifrice forward into the bore

13 against the piston 15 moving it so that it overruns the port 10 allowing the charge of dentifrice to issue between the bristles of the brush. Upon release of the pressure 5 upon the collapsible tube 23, spring 16 forces piston 15 back so that it overruns the port 10 abuts valve seat 9 tightly closing port 13, and prevents dentifrice from further issuing through the port.

10 Collapsible tube 23 may be of some ductile material such as lead, which is commonly employed for paste containers, or it may be a collapsible tube of rubber or similar material which will expand after being compressed; so that a charge of liquid may be obtained by inserting the neck 22 into the dentifrice liquid collapsing the tube and then permitting it to expand, and allowing the vacuum in the tube to draw the liquid 15 into the tube.

To load the brush with tooth powder, handle 7 is unscrewed from the shank 8, cap 25 removed from handle 7 and the disk 27 inserted over the open end in shank 8 as 20 illustrated in Fig. 4. In this position of the disk 27 any dentifrice with which the handle 7 is loaded, will not pass into the brush back. Cap 25 is now replaced upon the handle 7 and the hollow compartment in said handle 25 is loaded with the tooth powder and then replaced upon shank 8 by screwing it thereon.

When ready to use the brush upon the teeth, the brush and handle are turned vertically, the end of the handle struck against

the hand or any suitable place, the powder dropping through perforations 26 filling the cap 25, which serves as a receiver for the tooth powder, and is so proportioned that it contains exactly one charge of tooth powder for cleaning the teeth. The cap 25 35 is conveyed to the bristles 11 and the powder then sprinkled over the bristles. The cap is then replaced on handle 7 closing it against loss of tooth powder, and the brush 40 is ready to be used on the teeth.

What I claim is:—

In a brush, a handle comprising the combination of a handle shank having a bore provided with means for securing a collapsible container thereto, a hollow handle detachably secured at one end to said shank and provided at the other end with a perforate closure plate; a closure cap having a recess for containing dentifrice detachably secured to the end of said handle opposite the said shank, and an imperforate plate arranged to be detachably disposed between said closure plate and said cap, or between said handle and said shank to close the bore in said handle.

In witness that I claim the foregoing I have hereunto subscribed my name this twenty-seventh day of February 1915.

EARL H. OBERTOP.
